United States Patent Office

Des. 182,966
Patented June 3, 1958

182,966

BOAT

Roland E. Ladewig, Fort Worth, Tex., assignor to Whitehouse Reinforced Plastics Company, Fort Worth, Tex., a corporation of Texas

Application October 8, 1956, Serial No. 43,271

Term of patent 3½ years

(Cl. D71—1)

FIG. 2.

FIG. 3.

FIG. 1.

FIG. 4.

FIG. 5.

FIG. 6.

Figure 1 is a perspective view of a boat showing my new design;

Figures 2 and 3 are front and rear ends, respectively; and

Figures 4, 5 and 6 are top plan, side elevation and bottom views, respectively.

I claim:

The ornamental design for a boat, substantially as shown.
